SYNCHRONIZING MEANS FOR MOVING PICTURE AND TALKING MACHINES

Filed March 10, 1927

UNITED STATES PATENT OFFICE

LOUIS KOVACS, OF THROOP, PENNSYLVANIA

SYNCHRONIZING MEANS FOR MOVING PICTURE AND TALKING MACHINES

Application filed March 10, 1927. Serial No. 174,187.

This invention relates to a new and useful device in the nature of a combined moving picture and talking machine, adapted particularly for use in theatres, public halls, lecture rooms, and the like, as a means of projecting moving pictures on a screen and reproducing any desired accompanying dialect, lecture, or descriptive talking, as may be required to more fully convey the meaning or theme of the moving picture.

The object of the invention is to provide a combined moving picture and talking machine of novel construction and arrangement of parts, hereinafter more fully described, 15 claimed and illustrated in the accompanying drawing.

Fig. 1 illustrates my improved combined moving picture and talking machine, as same would appear when installed in a theatre 20 ready for use.

Fig. 2 is a side elevational detail view of the adjustable magazine stand adapted to hold the records.

Fig. 3 is a transverse vertical sectional view 25 taken on the line 3—3 of Fig. 2.

Fig. 4 is a detail central sectional view of the clutch mechanism for synchronizing the moving picture and talking machine reproduction.

As here embodied my improved device 30 comprises a moving picture machine 10, of ordinary construction such as generally used, having a projector 11, by which any desired moving picture may be projected upon a screen 12. The moving picture machine 10, is mounted on a base 12', provided with lower extended elements 13, or legs, adapted to support the said moving picture machine. The talking machine 14, or phonograph, is housed 35 in a suitable case, and is provided with a cover 15, preferably of glass, celluloid, or the like, so as to provide a dust proof removable cover member.

In Fig. 1 of the accompanying drawing, 40 I have shown my improved device in place, on an elevated platform 16, and I have provided a stairway 17, as a means of egress thereto. The latter described elements, being common to a public hall, theatre or the like, 45 which is provided with the usual seats 18, and

the boxes 19 for reserved seating arrangement.

The talking machine 14, is provided with the loud speaker 20, operatively connected thereto, and provided with the usual magnifying means, so as to produce the required volume. The ear phones 21, are operatively connected to the talking machine 14 and are conveniently located in the above mentioned boxes 19, adjacent to the seats 22, so as to permit the occupants of the seats 22, in the boxes 19, to easily hear the talking machine 14.

In Figs. 2 and 3 of the accompanying drawing, I have shown the talking machine 14, provided with the usual reproducer 23, and 55 needle 24, removably attached thereto, in the ordinary well-known manner. The reproducer 23, is mounted on the free extremity of the reproducer arm 25, pivotally attached as 60 to 26, to the case 27.

The records 27, such as ordinarily used in talking machines, are of hollow cylindrical construction, and are adapted to removably engage the extended elements 28, or arms 70 rotatively attached to and extended horizontally from the spider member 29. The pinions 30, are attached to the arms 28, and mesh with the gear 31 attached to the arms 28, and mesh with the gear 31, attached to the shaft 32. The shaft 32, rotatively supports the spider member 29. The shaft 32, is rotatively mounted in the bracket 33, attached to the case 27'. The sprocket wheel 34, is attached to the shaft 32.

The above described construction being 85 such as will permit the records 27, to be rotated when the sprocket wheel 34 is rotated.

The lever 35, is pivotally attached, at one extremity, as at 36, by a pin, or the like, carried in the bracket 37, attached to the case 90 27'. The lever 35, is provided with a handle element 38, at its free extremity, and is provided with a raised intermediate portion 39, adapted to engage any desired one of the notches 40, formed in the spider member 29, 95 adjacent to the arms 28. The lever 35, is normally held in the above mentioned engagement, by means of the expansion spring 41, positioned under the lever 35. The latter described construction being such as will per- 100

mit any desired one of the records 27, to be held in the required position, so as to permit the needle 24 of the reproducer 23, to make contact therewith, as clearly shown in Fig. 5, as is required to play the record.

In Fig. 5 of the accompanying drawing, I have shown the operating handle 50, of the moving picture machine 10, attached to the crank 51, which is pivotally attached, as at 10 52, by a pin or the like to the shaft 53. The reel 54 such as commonly used to carry the film 55, such as ordinarily used in moving picture machines, and which contains the views of the moving picture, is attached to the 15 shaft 53. The above construction being such as will permit the handle 50, when turned or rotated, to move or travel the film 55, which in conjunction with the ordinary commercial elements of the above mentioned moving picture machine 10, projects the moving picture 20 on the screen 12, visible to the audience.

In Fig. 4 of the accompanying drawing, I have shown the disc member 56, rotatively mounted on the shaft 53. The ring shaped 25 member 57, is attached to the disc member 56, and has formed, or cut on its outer periphery sprocket teeth 58, over which the sprocket chain 59, is extended. The sprocket chain 59, is also extended over the above mentioned 30 sprocket wheel 34. The ring shaped member 57 is provided with a tapered, or frustum conical shaped portion 60, adapted to be engaged by the cover member 61, which has attached thereto a facing 62, preferably of 35 leather, or the like. The cone member 61, is slidably mounted on the shaft 53, and is attached thereto, by means of the keys 62', attached to the shaft 53, and extended therefrom, engaging in recesses formed in the hub 40 63, of the cone member 61. The expansion spring 64, is wound or positioned on the shaft 53, intermediate the collar 65, attached to the shaft 53 and the hub 63, of the cone member 61, so as to normally hold the cone member 61, 45 in engagement with the ring shaped member 57. The above described construction being such as will permit the handle 50 when rotated, to rotate the above mentioned talking machine records 27, and to move or travel the 50 reel 55, as above set forth. The crank 51, is provided with an extended portion 66, adapted to engage or strike the cone member 61, so as to disengage the cone member 61, 55 with the ring shaped member 57, when the handle 50, is pressed or forced inwardly. The above described construction being such as will permit the talking machine 14, to stop, so as to synchronize the words from the talking machine with the picture projected from 60 the moving picture machine.

The crank 51, is provided with a second extended portion 67, comparatively shorter than the above mentioned extended portion 66, adapted to engage or strike the ring shaped 65 member 57, when the crank 51 is forced fur-

ther inwardly than above mentioned, to engage the ring shaped member 57, so as to momentarily operate the talking machine 14, to facilitate the above mentioned synchronizing of the said talking machine and moving 70 picture machine.

It being understood that the talking machine 14, is provided with the usual speed regulator 14'.

Having thus described my invention, what 75 I claim as new and desire to secure by Letters Patent of the United States is as follows:

1. The combination with a driven member, of a shaft firmly connected with said driven member, a disc member rotatively mounted on the shaft, a ring member attached to the disc for driving a second member, and formed with sprocket teeth, said ring member being provided with a frustum conical portion, a cone member keyed to the shaft and slidably mounted and capable of frictionally engaging the frustum conical portion, means for normally urging these parts into engagement, a crank connected with the shaft, and an extended portion thereon abuttable against the cone member upon depression of the crank to disengage the cone member from the conical portion so as to permit the sprocket chain to stand still so as to synchronize the driven member therewith. 95

2. The combination with a driven member, of a shaft firmly connected with said driven member, a disc member rotatively mounted on the shaft, a ring member attached to the disc for driving a second member, and formed with sprocket teeth, said ring member being provided with a frustum conical portion, a cone member keyed to the shaft and slidably mounted and capable of frictionally engaging the frustum conical portion, a spring coaxially arranged on the shaft and acting between the cone member and a flange on the shaft for normally urging the cone member into engagement with the said frustum conical portion, a crank connected with the shaft, and an extended portion thereon, abuttable against the cone member upon depression of the crank to disengage the cone member from the conical portion so as to permit the sprocket chain to stand still so as to synchronize the driven member therewith. 110

In testimony whereof I have affixed my signature.

LOUIS KOVACS.
